UNITED STATES PATENT OFFICE.

GUY M. GREEN, OF WALLA WALLA, WASHINGTON.

DIVIDER FOR MOWING MACHINES.

Application filed June 28, 1924. Serial No. 722,915.

To all whom it may concern:

Be it known that I, GUY M. GREEN, a citizen of the United States, residing at Walla Walla, in the county of Walla Walla and State of Washington, have invented certain new and useful Improvements in Dividers for Mowing Machines, of which the following is a specification.

This invention relates to dividers for mowing machines and has as one of its objects to provide a divider that is adaptable to any divider shoe and that may be easily attached thereto.

Another object of the invention is to provide a divider that will divide the grain and that will automatically adjust itself with the adjustment of the sickle bar.

A further object of the divider is to provide a divider that is flexible to move with the vertical acting guide board.

A further object of the invention is to provide a divider that is cheap to manufacture, that requires no independent adjustment, and that is easy to install.

With these and other objects in view reference is now had to the accompanying drawings in which

Fig. 1 is a side elevation of the device attached to a divider shoe;

Fig. 2 is a side elevation of the device attached to a divider shoe and in an adjusted position.

Fig. 3 is a plan view of the device as attached to a divider shoe.

Having reference to the drawings like numerals refer to like parts throughout the several views and the numeral 1 refers to a divider shoe on the lower side of which is a hingedly mounted runner 2 provided with a connecting piece 3 rigidly attached to the runner and extended in a generally upward direction to engage the shoe 1 by means of a runner fastening bolt 4 that is secured in the slot 5 and the connecting piece 3 for sliding adjustment in said slot.

By means of this bolt the runner may be raised or lowered, as shown in Fig. 2, on the hinge portion 6.

It is obvious now that as the bolt moves with the connecting piece and runner that any part attached to this bolt will move with it. The bolt therefore will be utilized in this invention in a manner to be explained.

At the rear end of the divider shoe is a

guide board 7 attached thereto by means of a yielding connection consisting of a bolt 8, a nut 9 threadedly engaged thereon, with a spring 10 interposed between the nut and the guide board and bearing thereagainst to provide for vertical movement of the guide board on the bolt.

The divider shoe is provided with an inward curvature and the guide board is so attached to the shoe as to form a continuation of that element, with its rear end 11 brought inward considerably beyond the outer end of the divider shoe.

Intermediate the ends of the guide board is secured a fender arm 12 which is also brought inward from the guide board.

By this arrangement grain, standing under ideal conditions, when cut will be turned to fall inward and will leave a mark of separation between the cut and standing grain.

For this purpose a dividing rod 13 is designed which consists of a body portion provided with a cup 14 or other means for pivotally engaging the end 15 of the divider shoe 1, and provided on its rear end with a yoke 16 that is adjustably engageable with the runner fastening bolt 4, the yoke being of sufficient length to make the device adaptable to shoes of various sizes. A finger portion 17 extends in a generally upward and forward direction from the pivotal point, for parting the grain, and carries a yielding guard 18 that is suitably attached as at 19, to the finger the guard extending rearwardly in a continuous, substantially horizontally curved line engagement with the fender arm 12.

By this arrangement I provide a support for the guard at both ends thereof and also provide for a continuous, uninterrupted guard from the finger to the fender arm, thus eliminating central supports that would form an obstruction to catch and bunch up the grain.

In tall grain the sickle 20 is raised by loosening the runner fastening bolt 4 and forcing the runner downward on the hinge 6. By this adjustment, the bolt 4, the yoke 16 attached thereto, and the runner 2 are moved downwardly thus raising the finger 17 on the pivotal connection 14. It will be observed that due to the greater weight on the rear side of the divider shoe, the entire mechanism will take the position shown in

Fig. 2, the sickle being raised and the rear curved portion of the runner resting on the ground.

To start the grain leaning the yielding guard 18 is attached at one end to the finger intermediate the ends thereof, to bring the guard sufficiently low to catch the body of the grain, and from the point of attachment (19), which may consist of any suitable means, the guard is curved and extends rearward following a path generally concentric with the general curve of the dividing shoe, guide board and fender arm, but inward therefrom to a point approximately over the point of the first guard 22 of the sickle.

By this means the grain is started leaning before it is cut and thus immediately upon being cut is free to the continued influence of the yielding guard, assisted by the guide board and fender arm, to be laid back from the uncut grain and provide a well defined path between the standing and fallen grain, so that subsequent rounds made by the mower will not encounter and cut over the fallen stuff.

As above mentioned the guide board is designed to move in a vertical plane as shown by the dotted lines in Fig. 1. This movement will occur upon uneven ground or upon striking rocks or other obstructions and obviously the fender arm will move with the guide board. Now as it is desirable to have flexibility in the yielding guard it is necessary to secure its rear end 23 to prevent excessive lateral motion. This end portion thereof is adjustably secured to the fender arm by means of a staple 24, or other means, and the guard is slidably mounted therein so as to provide a free sliding movement and yet secure the guard against lateral motion.

In use the divider is attached to the divider shoe as above explained and as the mower enters the standing grain the finger

will divide the grain and the yielding guard will cause a portion of the grain that lays in front of the mower to fall away from the edge of the swath upon being cut.

Upon raising the sickle for high grain, in the manner above explained, the finger is automatically raised also. This act further raises the front of the yielding guard with the finger and thus provides perfect cooperation of these two members.

At the same time the vertical movement of the fender arm is not interfered with and the yielding quality of the yielding guard provide for any temporary lateral movement that might be caused by, say, a heavy mass of grain being momentarily encountered.

As the grain is now laid back from the standing grain the inner portion of the sickle (not shown) remains free of any obstruction and thus provides for the lightest draft possible.

It is obvious that the invention is equally applicable to alfalfa and other similar grain; that it may be attached without alteration of the shoe; and that the finger will force any tangled stuff below the shoe and thus prevent it from lodging thereon.

Having thus described my invention, I claim—

In a divider for mowing machines, the combination with a dividing shoe having a removable guide board and fender arm, and a dividing rod having a finger portion, suitably attached to said shoe, of a yielding guard supported at one end by the said finger portion and at its other end by a sliding connection attached to said finger arm, said guard being formed in a generally horizontally curved line and positioned to produce a continuous, uninterrupted guard from the finger portion to the end of the fender arm.

In testimony whereof I affix my signature.

GUY M. GREEN.
